UNITED STATES PATENT OFFICE.

ELLIS W. COOPER, OF NEW YORK, N. Y., ASSIGNOR TO PLANOGRAPHIC EQUIPMENT COMPANY, A CORPORATION OF NEW YORK.

SHEET-HANDLING MACHINE.

1,364,983.

Specification of Letters Patent. Patented Jan. 11, 1921.

Application filed June 5, 1919. Serial No. 301,864.

To all whom it may concern:

Be it known that I, ELLIS W. COOPER, a citizen of the United States, residing in the city and State of New York, have invented 5 certain new and useful Improvements in Sheet-Handling Machines, of which the following is a specification.

The invention relates to printing presses and more especially to sheet cutting, collecting and delivering mechanism for a web press, the invention in certain aspects thereof being especially directed to a delivery mechanism especially designed and capacitated for handling sheets of very thin paper.

10 15 Further objects and advantages of the invention will be set forth in part hereinafter, and in part will be obvious herefrom, or may be ascertained through practice with the invention; the same being attained and 20 realized through the instrumentalities and combinations pointed out in the appended claims.

The invention consists in the novel parts, constructions, arrangements, combinations 25 and improvements herein shown and described.

The accompanying drawings, referred to herein and constituting a part hereof, illustrate one embodiment of the invention, and 30 together with the description, serve to explain the principles of the invention.

Of the drawings:

Figure 1 is a side elevation of a machine constructed in accordance with the invention;

35 Fig. 2 is a fragmentary detail elevation, on an enlarged scale, showing the transfer of the sheets from the delivery cylinder to the bed;

40 Fig. 3 is a fragmentary detail elevation, on an enlarged scale, looking at Fig. 2 from the right, showing the bed only but including details of the height regulating devices therefor;

45 Fig. 4 is a fragmentary detail elevation, on an enlarged scale, showing a gripper mechanism for retaining the sheets on the bed;

50 Fig. 5 is a fragmentary detail elevation corresponding to Fig. 4, and looking thereat from the right;

55 Fig. 6 is a fragmentary front elevation, on an enlarged scale, looking at Fig. 1 from the right; and

Fig. 7 is a top plan of the delivery bed and its drive detached from the machine.

It is desirable and advantageous to print at high speed upon very thin paper, such as tissue paper, and to deliver the printed sheets in a pile or stack. Tissue paper and other thin papers, however, are very difficult to handle in a machine, and the present invention in certain of its main features is directed toward the delivery of sheets of tissue or other very thin papers, and especially the delivery of such sheets of relatively large size. In certain aspects, the invention provides for the delivery either singly or in collected groups of the thin sheets flat, sheet after sheet, or group after group of sheets, on top of a stack. The invention also provides for cutting the sheets from the running printed web, and for collecting them when so desired.

The invention in one of its aspects, provides for delivering the thin sheets by laying them out upon a support with the air pressed out from beneath and the sheets being held in delivered position at a plurality of points. This action is repeated successively, the so delivered sheets being built up 80 into a stack. Other features and objects of the invention will be stated or indicated hereinafter in connection with the detailed description of the illustrated embodiment.

Referring by way of example to the illustrated embodiment, and describing first the printing mechanism, in order to follow the material in its passage through the machine, a planographic, offset printing press is provided, printing upon a web of paper α running through the machine. The illustrated form of press referred to is provided with a form cylinder 1 having planographic printing plates, usually consisting of flexible sheets of zinc or aluminum, mounted upon 90 the surface of the cylinder in the usual manner. A damping mechanism, indicated generally by 2, is provided, and also suitable inking mechanism 3, all of which may be of usual or other approved or suitable form.

100 The printing plates upon the cylinder 1 print upon the surface of an offset or transfer cylinder 4, having suitable impression receiving and impression imparting surfaces, such as rubber blankets or the like, 105 the cylinder and offset surfaces likewise being of usual or approved form. Coöperating with the offset cylinder 4 is an impression cylinder 5, the web α being drawn from a roll γ and being printed upon by the cylind- 110

der 4 as it passes through the impression between the cylinders 4 and 5. The web is shown guided over rollers 6, 7 and 8, the roller or rollers 8 being preferably propeller 5 or driving rollers.

Means are provided for cutting the printed sheets from the web, and also for collecting the sheets prior to delivery, when this is desired, whereby the sheets may be delivered 10 singly or in groups, as may be preferred or found convenient. In the embodied form of mechanism, two coöperating cylinders are provided which cut the web into sheets, one of the cylinders also acting either as a sheet 15 collecting cylinder or as a single sheet delivery cylinder when desired. This cylinder in the present embodiment also coöperates with a reciprocating bed to deliver the sheets as hereinafter described.

20 Referring first to the cutting operation, a cylinder 10 is provided having a cutting blade 11, which is rendered alternately operative and inoperative, that is, it is in cutting position on one revolution of the cylinder 10 and is then silenced for one or more revolutions of the cylinder 10, this cylinder being of less diameter than the delivery cylinder 12. In the present embodiment a sheet is cut on every revolution by cylinder 25 12. The cylinder 12 is provided with a cutting member 13, coöperating with the blade 11 on the cylinder 10 to sever the sheets successively from the web.

Sheet holding means are provided on the cylinder 12 of suitable form, and as embodied comprise a row of impaling pins 14 which impale the head of the sheet across the cylinder 12 to hold the sheet thereon. The pins 14 are longitudinally movable, and 35 are retractable within the cylinder 12 to deliver either a single sheet, or a group of collected sheets, from the cylinder 12. Suitable operating means are provided for controlling the movements and positions of pins 40 14. In the embodied form thereof, each of the pins 14 is carried in a bearing aperture in the cylinder 12, and at its inner end each pin is pivotally connected to a corresponding arm 15. The arms 15 are fixed to a shaft 45 16 mounted transversely in the cylinder 12. Fixed to one end of the shaft 16 and located exteriorly to the cylinder 12 is a cam-operated actuating arm 17. Mounted upon the machine frame is a cam 18, which engages with the arm 17, or a cam roll thereon, to retract the pins 14, the pins being held in the projected or sheet engaging position by a spring acting on the shaft 16, which may be of the usual construction, and 55 60 is not shown.

Means are provided for controlling the retraction and projection of the impaling pins 14 to effect the delivery of the sheets singly, or for collecting them and delivering 65 them in groups, from the cylinder 12.

For this purpose, as embodied, the cam 18 is not mounted directly on the machine frame, but it is carried upon an arm 19, which arm is pivotally supported at 20 upon the machine frame. The other end of the lever 70 arm 19 is pivotally connected at 21 to a rod 22, which rod is actuated by a suitable cam (not shown) to move the cam 18 into and out of coöperating relation with the arm 17.

When the mechanism just described is in 75 the position shown in Fig. 2, the cam 18 engages the arm 17, and thereby rocks shaft 16 to retract the impaling pins 14 within the cylinder 12, thus releasing the sheets on the cylinder 12 to permit their being taken 80 by the coöperating delivery devices. As the arm 17 moves off the cam 18, the spring of shaft 16 will impart thereto a slight rocking motion and the impaling pins 14 will again be projected to the sheet-taking position. 85 When the lever arm 19 is rocked upwardly at the left and downwardly at the right in Fig. 2, cam 18 is moved out of engaging position with respect to the arm 17, and the impaling pins are not retracted on that revolution of the cylinder, in which case the sheet is not delivered but travels on with cylinder 12. By timing the movements of the arm 19 and consequently the position of cam 18, two or more sheets may be collected 90 upon the cylinder 12 and be delivered together in a group.

Delivery means are provided by the invention capacitated and especially designed for the delivery and smooth laying out one 100 upon the other of large sheets of tissue paper or other very thin sheets, either singly or in groups. In certain aspects of the invention, these delivery devices comprise a traveling bed coöperating directly with the 105 delivery means, such as the cylinder 12 or other delivery device, to engage the delivered sheet, or group of sheets, at the head thereof and also at various separated points along the sheet or sheets, to lay them down 110 smoothly on the top of the stack or pile of delivered sheets and to hold them as laid. Coöperating therewith are provided means for maintaining the top of the stack or pile of sheets at a uniform or constant level or 115 relation with the cylinder 12, or other sheet delivery device. Means are also provided for moving the cylinder 12, or other corresponding device or mechanism, and the sheet receiving bed toward and from each 120 other to provide for the delivery of the sheets in groups and for the idle or return travel of the bed.

In the embodied form of the means above referred to, a horizontally reciprocable bed 125 25 travels to and fro on guideways 26 (see especially Fig. 3) in the machine frame, the bed 25 being preferably provided with rollers 27 running on the guides 26. In the embodied form of actuating mechanism for 130

the bed 25, an endless sprocket chain 28 is provided running over an idler sprocket 29, which is journaled in the machine frame, and over a driven sprocket wheel 30, likewise mounted on the machine frame at or beyond the other end of the travel of the bed 25. Fixed to the chain 28 is a pin 31 projecting into a groove 32 formed in the bottom of the frame of the table 25. Thus 5 as the pin travels along one of the straight reaches of the chain 28, the bed 25 is carried at uniform speed in one direction, and as the pin 31 passes around the sprocket wheel at either end, the bed slows down, 10 reverses its direction at the dead center of the sprocket wheel, picks up speed as the pin 31 travels about the sprocket wheel, and as it reaches the transverse diameter thereof, the bed 25 is traveling at full speed in the 15 opposite direction. The pin 31 will move to and fro in the slot 32 dependent upon its location on the parallel reaches of the chain 28, and as it passes about the two sprocket wheels. The bed is connected to travel at 20 the surface speed of the cylinder 12 while the sheet or sheets are being transferred from the cylinder to the bed. The speed of the bed may be varied at other times to provide for the delivery of different numbers 25 of sheets and to avoid, if desired, idle reciprocations of the bed. So far as concerns many features of the invention, other and any convenient or suitable driving means may be provided for the bed 25.

30 The illustrated form of driving means for sprocket wheel 30 comprises a shaft 33 upon which sprocket wheel 30 is fixed. Fixed also on shaft 33 is a pinion 52, meshing with a pinion 53 on a shaft 54. On shaft 40 35 54 is a bevel gear 34, which meshes with a bevel gear 35 on shaft 36, which shaft is driven in any suitable manner.

The embodied form of means for maintaining the top of the pile or stack of delivered sheets z in uniform or constant relation 45 or position with respect to the cylinder 12, or corresponding device, during the delivery, comprises a sheet support 40, mounted for vertical movement on the bed 25 (see Figs. 2, 3 and 7). The sheet support 40 is mounted at its corners upon vertically disposed screw rods 41, with the upper ends rotatably connected to bosses 42 on the bottom of the sheet support 40. The screw 50 55 rods 41 are in threaded engagement with screw-threaded apertures 43 in the bed 25. One of the screw rods 41 is provided at its lower end with a star wheel 44 fixed thereto, and which is actuated by a suitable trip 60 65 on the machine frame on each reciprocation of the bed 25. The screw rods 41 are caused to move together by suitable means, and as embodied each screw rod 41 has fixed thereto at its lower end a sprocket wheel 45, and a sprocket chain 46 runs over the four

sprocket wheels 25 thus causing the screw rods 41 to rotate together, and as the bed 25 reciprocates, the sheet support 40 is gradually lowered on successive reciprocations of the bed so as to compensate for the growing thickness of the sheet stack z as the sheets or groups of sheets are successively deposited thereon. Sprocket chain 46 may also run over tensioning and guiding idlers 51. 70 75

Means are provided for engaging the sheets as they are delivered to the bed 40 or to the stack z of sheets thereon, and for holding the sheets as delivered in position on the bed or stack, and in the preferred 80 form such sheet holding means act on the delivered sheets not only at their heads but at a plurality of separated points along the sheet or sheets, this feature being especially desirable with sheets of tissue paper or 85 other thin paper. In accordance with one feature of the invention, these means engage the sheet or sheets at or immediately prior to the instant when any such point of engagement on the sheet leaves the cylinder, 90 whether such point is the head of the sheet or some point farther along the side of the sheet.

In the form of such sheet holding means for the delivery bed, shown in Figs. 1, 2 95 and 3, impaling pins 47 are provided, arranged transversely across the bed 25 and projecting upwardly in front of or through the sheet receiving bed 40. The position of these pins is such that they will impale 100 the head of the sheets as they pass on the cylinder 12, and by the retraction of impaling pins 48 on the cylinder 12, the head of the sheet or sheets will be taken with the bed and laid upon the top of the sheet 105 stack z .

In the embodied form of means for holding the sheets along their length, as shown in Figs. 2 and 3 other impaling pins 48 are shown arranged along the bed 25 and along 110 the edges of the sheet stack z . Co-operating recesses 49 are preferably provided in the cylinder 12, behind the sheet or sheets thereon. The sheets are pressed over the pins 48 as the successive pins pass the point of 115 contact between the cylinder 12 and the top of the sheet stack z , as will be understood from Figs. 1 and 2, the sheets thus being held at a plurality of points across the head and along each side thereof, and if desired 120 across the tail of the sheet, as the various parts of the sheets leave the cylinder 12 and are laid along the top of the stack z . Thus the air is pressed out from beneath the sheets, and they are firmly held at a plurality of points as they are laid upon the top of the stack or pile z .

In Figs. 4 and 5, grippers are shown for engaging the sheets and holding them upon the top of the stack z in lieu of the impal- 130

ing pins, although for most classes of work as on very thin papers, the impaling pins are not objectionable. In the embodied form of gripping mechanism, a supporting 5 plate 55 extends upwardly from the bed 25 and is provided with supporting brackets or lugs 56. The grippers 57 are carried upon arms 58 pivotally mounted on pins 60, supported by the brackets 56. Pins 60 are held against rotation by suitable means, the embodied form showing a nut 61 threaded 10 on the end 62 of the rod 60, which rod is shouldered against the opposite side of the bracket 56, as shown in Fig. 4.

15 The gripper arm is pivotally mounted on the rod 60, and is impelled to the closing position by a spring 63, coiled about the rod 60 and having one of its ends fixed to the gripper and the other end fixed to the head 20 64 of the rod 60. The tail 65 of the gripper arm has a cam roller 66, which is actuated by a cam 67, located on the machine frame in position to open the gripper as the sheet or some desired point in the sheet is laid on 25 the stack, and permitting the gripper to close immediately afterward on the just laid sheet. The cylinder 12 is provided with apertures 68 to permit the grippers to swing in above and to immediately close upon the 30 sheets.

In the embodied form of means for moving the sheet supplying and sheet receiving elements of the delivery mechanism apart for the idle stroke or strokes of the 35 sheet receiving bed, the cylinder 12 is moved in its bearings. As embodied the shaft 70 of cylinder 12 is mounted at each end in an eccentric 71, which is journaled in the machine frame. The eccentrics 71 are provided 40 with arms 72, to which arms are pivotally connected reciprocable rods 73, working in apertures in lugs 74 on the machine frame. At their other ends, the rods 73 are provided with cam rollers 75 coöoperating with 45 cams 76 upon a shaft 77. Spring 78 working between the bearing lugs 74 and collars 79 on the rods 73 keep the rollers 75 to the cams 76. Suitable driving means are provided for the shaft 77, and as embodied a 50 bevel gear 80 is fixed on the shaft 77, and meshes with a bevel pinion 81 fixed on the shaft 82. Fixed also on the shaft 82 is a bevel pinion 83, meshing with a bevel pinion 84 fixed on shaft 36.

55 When it is desired to deliver the sheets from the cylinder 12 in groups of three, the driving chain will be three times the length of the circumference of cylinder 12, and the parts will be timed so that the head of the 60 sheet stack α will meet the head of the sheets on cylinder 12 on every third revolution of the cylinder. It will be understood that this particular arrangement is merely exemplary, as the timing and coöperation generally may be varied to deliver different

numbers of sheets at a time. The general operation of the machine will be fully understood from the explanations made hereinbefore in connection with the different devices and need not be operated.

70 From all the foregoing it will be understood that a mechanism has been provided realizing the objects and advantages set forth, together with other objects and advantages. It will be understood also that 75 changes may be made from the mechanism as shown and described without departing from the principles of the invention and without sacrificing its chief advantages.

What I claim is:—

80 1. A printing press delivery mechanism including in combination a reciprocating sheet receiving bed, a sheet carrying cylinder adapted to lay the front edge of its sheet directly on the head end of the bed, and means 85 for holding the sheet in laid position on the bed.

2. A printing press delivery mechanism including in combination a sheet carrying cylinder, a reciprocating sheet receiving bed, 90 means for transferring the sheets directly from the cylinder to the bed, and means on the bed engaging the sheets and holding them to the bed.

3. A printing press delivery mechanism 95 including in combination a sheet carrying cylinder, a reciprocating sheet receiving bed, and means for collecting a plurality of sheets upon the cylinder and transferring them together from the cylinder to the bed.

100 4. A printing press delivery mechanism including in combination a sheet carrying cylinder, a reciprocating sheet receiving bed, means for collecting a plurality of sheets upon the cylinder and transferring them together from the cylinder to the bed, and means on the bed engaging the group of sheets and holding it to the bed.

105 5. A printing press delivery mechanism including in combination a reciprocating sheet receiving bed, a sheet carrying cylinder having means for holding the sheet upon the cylinder and releasing it therefrom, the cylinder being adapted to lay the front edge of its sheet directly on the head of the bed, and means on the bed for holding the head of the sheet just as it is released by the sheet holding means on the cylinder.

110 6. A printing press delivery mechanism including in combination a sheet carrying cylinder, a reciprocating sheet receiving bed, devices operating to deliver the head of the sheets directly from the cylinder to the front of the bed and to lay the sheets along the bed as the cylinder rotates and the bed travels, 115 and means engaging the head of the sheets and holding them in position upon the bed.

120 7. A printing press delivery mechanism including in combination a sheet carrying cylinder, a reciprocating sheet receiving bed,

130

80

devices operating to deliver the head of the sheets from the cylinder to the front of the bed and to lay the sheets along the bed as the cylinder rotates and the bed travels, and

5 means engaging the sheets at a plurality of points along their length and holding them in position upon the bed.

8. A printing press delivery mechanism including in combination a sheet collecting 10 cylinder, a sheet receiving reciprocating bed, and devices operating to deliver the front end of a group of sheets from the cylinder to the front of the bed and to lay the group of sheets along the bed as the cylinder rotates and the bed travels.

9. A printing press delivery mechanism including in combination a sheet collecting cylinder, a sheet reciprocating bed, and devices operating to deliver the front end of a 20 group of sheets from the cylinder to the front of the bed and to lay the group of sheets along the bed as the cylinder rotates and the bed travels, and devices engaging the group of sheets and holding it to the bed.

25 10. A printing press delivery mechanism including in combination a sheet carrying cylinder, a reciprocating sheet receiving bed, and devices operating to deliver the head of the sheets at the instant of their release from the cylinder to the front of the bed and to lay the sheets along the bed as the cylinder rotates and the bed travels, and means for holding the sheets to the bed.

11. A printing press delivery mechanism 35 including in combination a sheet carrying cylinder, a reciprocating sheet receiving bed, and means for transferring the sheets from the cylinder to the bed, and means for regulating the height of the bed to the height of 40 the pile of delivered sheets.

12. A printing press delivery mechanism including in combination a sheet carrying cylinder, a reciprocating sheet receiving bed, means for transferring the sheets from the 45 cylinder to the bed, means on the bed engaging the sheets and holding them to the bed, and means for regulating the height of the bed to the height of the pile of delivered sheets.

50 13. A printing press delivery mechanism including in combination a sheet carrying cylinder, a reciprocating sheet receiving bed, devices operating to deliver the head of the sheets from the cylinder to the front of the bed and to lay the sheets along the bed as the cylinder rotates and the bed travels, and means for regulating the height of the bed to the height of the pile of delivered sheets.

14. A printing press delivery mechanism 60 including in combination a cylinder having sheet holding devices, a traveling sheet receiving bed coöperating with the cylinder, the sheet holding devices releasing the sheets from the cylinder as the head of the sheets 65 passes between the cylinder and the bed, and

devices on the bed successively engaging a sheet at a plurality of points along its length as the sheet is gradually laid along the bed from the cylinder.

15. A printing press delivery mechanism 70 including in combination a cylinder having sheet holding devices, a traveling sheet receiving bed coöperating with the cylinder, the sheet holding devices releasing the sheets from the cylinder as the head of the sheets 75 passes between the cylinder and the bed, and means on the bed engaging the released sheets.

16. A printing press delivery mechanism including in combination a cylinder having 80 sheet holding devices, a traveling sheet receiving bed coöperating with the cylinder, the sheet holding devices releasing the sheets from the cylinder as the head of the sheets passes between the cylinder and the bed, and 85 means for preserving the top of the sheet pile on the bed in constant relation to the cylinder.

17. A printing press delivery mechanism including in combination a cylinder having 90 sheet holding devices, a traveling sheet receiving bed coöperating with the cylinder, the sheet holding devices releasing the sheets from the cylinder as the head of the sheets passes between the cylinder and the bed, 95 and means on the bed engaging the released sheets, and means for preserving the top of the sheet pile on the bed in constant relation to the cylinder.

18. A printing press delivery mechanism 100 including in combination a sheet carrying cylinder, a reciprocating sheet receiving bed, means for transferring the sheets from the cylinder to the bed, and means for holding the sheets to the bed at both ends thereof. 105

19. A printing press delivery mechanism including in combination a sheet carrying cylinder, a reciprocating sheet receiving bed, means for transferring the sheets from the cylinder to the bed, and means for holding 110 the sheets to the bed at a plurality of points along the length thereof.

20. A printing press delivery mechanism including in combination a sheet carrying cylinder, a reciprocating sheet receiving bed, 115 and means for collecting a plurality of sheets upon the cylinder and transferring them together from the cylinder to the bed, and means for engaging and holding the successively delivered groups of sheets to the 120 bed.

21. A printing press delivery mechanism including in combination a sheet carrying cylinder, a reciprocating sheet receiving bed, 125 means for collecting a plurality of sheets upon the cylinder and transferring them together from the cylinder to the bed, and means for engaging and holding the successively delivered groups of sheets to the bed at both ends thereof. 130

22. A printing press delivery mechanism including in combination a sheet carrying cylinder, a traveling sheet receiving bed co-operating with the cylinder to receive the sheets as they pass between the rotating cylinder and traveling bed, and sheet retaining devices located at a plurality of points along the bed and engaging the sheets as the successive devices pass the cylinder in the travel of the bed.

23. A printing press delivery mechanism including in combination a sheet carrying cylinder, a traveling sheet receiving bed co-operating with the cylinder to receive the sheets as they pass between the rotating cylinder and traveling bed, and sheet retaining devices located at the head and at a plurality of points along the bed and engaging the sheets as the successive devices pass the cylinder in the travel of the bed.

24. A printing press delivery mechanism including in combination a sheet carrying cylinder, a traveling sheet receiving bed co-operating with the cylinder to receive the sheets as they pass between the rotating cylinder and traveling bed, and sheet retaining devices located at a plurality of points along the bed and engaging the sheets as the successive devices pass the cylinder in the travel of the bed, and means for maintaining the top of the sheet pile on the bed at a constant height with respect to the cylinder.

25. A printing press delivery mechanism including in combination a sheet carrying cylinder, a traveling sheet receiving bed co-operating with the cylinder to receive the sheets as they pass between the rotating cylinder and traveling bed, and sheet retaining devices located at a plurality of points along the bed and engaging the sheets as the successive devices pass the cylinder in the travel of the bed, and means on the cylinder for delivering the head of the sheets to the front of the bed.

26. A printing press delivery mechanism including in combination a sheet carrying cylinder, a sheet receiving bed, means for transferring a sheet from the cylinder to the bed, means for causing the bed and cylinder to move in sheet transferring relation in one direction of travel of the bed, and to space them apart while the bed is traveling in the opposite direction.

27. A printing press delivery mechanism including in combination a sheet carrying cylinder, a sheet receiving bed, means for causing the bed and cylinder to move in sheet transferring relation in one direction of travel of the bed, to space them apart while the bed is traveling in the opposite direction, and means on the bed for taking the head of the sheets from the cylinder while traveling in the sheet transferring relation.

28. A printing press delivery mechanism including in combination a sheet carrying cylinder, a sheet receiving reciprocating bed having a sheet support in varying positional relation to the cylinder as the height of the sheet pile varies and means in constant relation to the cylinder for receiving and holding the delivered sheets to the top of the pile.

29. A printing press delivery mechanism including in combination a sheet carrying cylinder, a reciprocating sheet receiving bed, and impaling pins on the bed receiving the sheets from the cylinder.

30. A printing press delivery mechanism including in combination a sheet collecting cylinder, a reciprocating sheet receiving bed, and impaling pins on the bed receiving the sheets from the cylinder.

31. A printing press delivery mechanism including in combination a sheet collecting cylinder, a reciprocating sheet receiving bed, and impaling pins at the head and along the sides of the bed receiving the sheets from the cylinder.

32. A printing press delivery mechanism including in combination a sheet carrying cylinder, a reciprocating sheet receiving bed, and impaling pins on the bed receiving the sheets from the cylinder, and recesses in the cylinder to receive the points of the pins.

33. A printing press delivery mechanism including in combination a sheet carrying cylinder, a reciprocating sheet receiving bed, impaling pins on the bed receiving the sheets from the cylinder and sheet holding means on the cylinder releasing the sheets when taken by the pins on the bed.

34. A printing press delivery mechanism including in combination a sheet carrying cylinder, a reciprocating sheet receiving bed, impaling pins on the bed receiving the sheets from the cylinder and impaling pins on the cylinder releasing the sheets when taken by the pins on the bed.

35. A printing press delivery mechanism including in combination a sheet collecting cylinder, a reciprocating sheet receiving bed, impaling pins at the head and along the sides of the bed receiving the sheets from the cylinder, and recesses in the cylinder to receive the points of the pins.

36. A printing press delivery mechanism including in combination a sheet carrying cylinder, a reciprocating sheet receiving bed comprising a sheet support and means for gradually lowering the sheet support as the sheets are delivered from the cylinder to the bed.

37. A printing press delivery mechanism including in combination a sheet carrying cylinder, a reciprocating sheet receiving bed, and means for transferring the sheets from the cylinder to the bed, a cylinder co-

operating with the sheet carrying cylinder, and coöperating sheet cutters mounted respectively on the two cylinders.

38. A printing press delivery mechanism including in combination means for holding a flat stack of sheets, sheet supplying means therefor, said means coöperating to gradually lay the sheets along said stack, and means for maintaining the top of the stack 10 at a constant level as the sheets are laid thereon.

39. A printing press delivery mechanism including in combination means for holding a flat stack of sheets, and sheet supplying 15 means therefor, said means coöperating to gradually lay the sheets along said stack while pressing the air out from beneath the laid on sheets.

40. A printing press delivery mechanism 20 including in combination means for holding a flat stack of sheets, sheet supplying means therefor, said means coöperating to gradually lay and press the sheets along said stack and devices engaging the sheets to hold 25 them to the top of the stack.

41. A printing press delivery mechanism including in combination means for holding a flat stack of sheets, sheet supplying means therefor, said means coöperating to gradually lay the sheets along said stack and devices engaging the sheets at a plurality of 30 points therealong to hold them to the top of the stack.

42. A printing press delivery mechanism 35 including in combination means for supplying a web, means for cutting sheets from the web, and means for gradually laying the cut sheets on the top of a stack.

43. A printing press delivery mechanism 40 including in combination means for supplying a web, means for cutting sheets from the web, means for gradually laying the cut sheets on the top of a stack and means for holding the sheets to the top of the stack at 45 a plurality of separated points along their length.

44. A printing press delivery mechanism including in combination means for supplying a web, means for cutting sheets from 50 the web, means for gradually laying the cut sheets on the top of a stack and means for holding the sheets at a plurality of separated points therealong to the top of the stack.

55. 45. A printing press delivery mechanism including in combination means for supplying a web, a cylinder and devices for cutting sheets from the web and holding them on the cylinder, and means coöperating with 60 the cylinder to lay them gradually along their length on the top of a sheet stack.

46. A printing press delivery mechanism including in combination means for supplying a web, a cylinder and devices for cut-

ting sheets from the web and holding them 65 on the cylinder, and a traveling bed, the cylinder and bed coöperating to lay the sheets gradually along their length upon a stack.

47. A printing press delivery mechanism 70 including in combination means for supplying a web, a cylinder and devices for cutting sheets from the web and holding them on the cylinder, and a traveling bed, the cylinder and bed coöperating to lay the 75 sheets gradually along their length upon a stack and means for holding the sheets at a plurality of separated points along their length to the stack.

48. A printing press delivery mechanism 80 including in combination means for holding a flat stack of sheets, sheet supplying means therefor, said means coöperating to gradually lay the sheets along said stack and devices at a plurality of points along each side 85 of the sheets for preventing movement of the sheet relatively to the stack of sheets.

49. A printing press delivery mechanism including in combination means for holding a flat stack of sheets, sheet supplying means 90 therefor, said means coöperating to gradually lay the sheets along said stack and devices at a plurality of points at the head of the sheets and along the side thereof for preventing movement of the sheet relatively to 95 the stack of sheets.

50. A printing press delivery mechanism including in combination means for holding a flat stack of sheets, sheet supplying means 100 therefor, said means coöperating to gradually lay the sheets along said stack and devices at a plurality of points at the head of the sheets and along each side thereof for preventing movement of the sheet relatively to 105 the stack of sheets.

51. A printing press delivery mechanism including in combination means for holding a flat stack of sheets, sheet supplying means therefor, said means coöperating to gradually lay the sheets along said stack and impaling pins on the stack holding means for holding the laid on sheets. 110

52. A printing press delivery mechanism including in combination means for holding a flat stack of sheets, sheet supplying means 115 therefor, said means coöperating to gradually lay the sheets along said stack and impaling pins at the head of the stack holding means for holding the laid on sheets.

53. A printing press delivery mechanism 120 including in combination means for holding a flat stack of sheets, sheet supplying means therefor, said means coöperating to gradually lay the sheets along said stack and impaling pins along a side edge of the stack 125 holding means for holding the laid on sheets.

54. A printing press delivery mechanism

including in combination means for holding a flat stack of sheets, sheet supplying means therefor, said means coöperating to gradually lay the sheets along said stack and im-
5 paling pins along both side edges of the stack holding means for holding the laid on sheets.

In testimony whereof, I have signed my name to this specification, in the presence of two subscribing witnesses.

ELLIS W. COOPER.

Witnesses:

WILLIAM H. LONG,
H. WHEELER CHATFIELD.
